Harry W. Bowen.
ATTORNEY.

UNITED STATES PATENT OFFICE

ALOYSIUS W. CORRIVEAU, OF WEST SPRINGFIELD, MASSACHUSETTS

ADJUSTABLE SPRING AND AXLE WEDGE

Application filed June 30, 1932. Serial No. 620,110.

This invention relates to improvements in adjustable spring and axle wedges, or pads, for counteracting or correcting the axle 5 caster, or twist, of the front axle of a motor vehicle, when the correct position of the king pin has been thrown out by reason of a slight bend, or twist of the axle, due to accidents, or otherwise.

Heretofore, it has been the practice to insert a wedge between the lower leaf of the front springs and the front axle, but no means is provided for accurately adjusting and bringing the axle back into its correct vertical, or other position, either forward or backward.

The present invention comprises a wedge device that is composed of two members, each being formed with intermeshing, or nesting teeth; one of them being placed on or attached to the front axle, and the other between the lower leaf of the spring and the member on the axle, the member under the springs being the adjustable one, either forward or backward. The intermeshing teeth of each of the members of the wedge are formed on the same arc of a circle, and the distance between one tooth and the next corresponds to an adjustment of 1° , so that several degrees of adjustment may be made in practice. Reference to suitable tables, known as "Front axle repair data", which have been prepared for re-setting, or positioning, a front axle, exactly, the movable wedge member may be set from 1° to 5° , as will be described.

The wedge construction is further so constructed that the upper wedge member that is located immediately beneath the lower leaf of the front springs may be reversed, end for end; that is to say, by having one end thicker, and placing this end at the front side of the axle, instead of at the rear side of the axle, whereby a greater tilt, or adjustment, in degrees, may be obtained.

In the present invention, it is possible to effect an adjustment of 5° , by reason of the reversible feature of the upper, or movable member of the wedge.

The invention, therefore, broadly comprises a wedge member formed in two parts

having intermeshing teeth, one of the members being placed on the upper surface of the front axle, and the other member directly under the leaves of the spring. The lower member is provided with an opening, or recess, to receive the usual pin on the lower leaf.

Referring to the drawing:

Fig. 1 is a vertical sectional view on a plane transverse to the front axle, showing a plurality of the front spring leaves in section and the two-part wedge device inserted between the lower leaf and the upper surface of the axle.

Fig. 2 is an elevational view showing the two wedge members removed and with the upper wedge member in a position indicating a caster adjustment of 2° and the thicker end of the upper member of the wedge being at the rear.

Fig. 3 is a top plan view of the two members assembled, as in Fig. 2, and showing the recess in the lower wedge member, which receives the pin on the lower leaf of the springs, and

Fig. 4 is a view similar to Fig. 2, but with the upper member of the wedge reversed with the thickened end at the front to indicate a caster adjustment of 5° .

Referring to the drawing in detail:

1 designates the front axle of a motor vehicle having the usual upper and lower flanges 2 and 3 and the web member 4. 5 indicates a plurality of the leaves of the front spring, the ends of which are shown broken off; 6, the lower leaf of the springs. 7 indicates the usual U-shaped clamping members for securing the spring to the axle.

Referring now to the details of the wedge device: 8 indicates the lower member and 9 the upper member. The member 8 is formed with a lower flat surface 8', which rests on the upper flat surface of the axle. Each of these members is formed with a series of V-shaped teeth 10 and 11, which intermesh and the distance, or pitch of these teeth represents 1° in distance, when considered with reference to a circle, the radius of which has been carefully determined to provide for this 1° of adjustment. The

lower member 8 is provided with a downwardly extending pin 12, which enters the opening 1' of the axle. This is formed with the integral upwardly extending boss 13 having the opening 14, which receives the usual pin 14' on the lower leaf 6 of the spring. The upper wedge member 9 is formed with the rectangular-shaped opening, or slot 15, to receive the boss 13 of the lower member, whereby the upper wedge member 9 may be adjusted lengthwise, relative to the lower wedge member 8. The adjustment of 1° between each of the V-shaped teeth 10 and 11 is indicated in Fig. 4, at 16. The adjustment of the upper movable wedge member 9, relative to the fixed member 8 is indicated in Fig. 2 at 17, where a 2° adjustment is shown. In this figure, the thickened portion 9' of the wedge is located at the rear side of the axle, which position is also indicated in Fig. 1. In the event that it is necessary to make a greater adjustment than 2° for tilting the spring; the thickened part 9' of the member 9 is placed at the front of the axle, as shown in Fig. 4, whereby a 5° adjustment may be effected, as indicated at 18.

It will be seen, from this description, that in order to compensate for the caster or twist of a front axle that is out of correct alignment, it is only necessary to loosen the clamping bolts 7 and jack up the front springs of the car to permit the upper wedge plate member 9 to be adjusted the desired number of degrees or teeth, as shown at 17, or 18, with reference to the data chart for any given make of car. It is to be understood that the whole wedge device, or pad, may be inserted, when the car is first assembled at the factory with the zero mark of the wedge to indicate the vertical alignment.

It will also be seen, after the adjustment has been made and the bolts 7 are tightened, there is no possibility of the wedge members slipping out of place and destroying the adjustment, since the intermeshing teeth 10 and 11 will retain the members in place. It is to be understood that I do not limit myself to a construction of a 1° adjustment, as in practice 1/2° adjustments are made. A 1/2° adjustment simply means varying the length of the radius and the distance between the teeth of the wedge members, whereby a finer adjustment may be made.

What I claim is:—

1. In a device for adjusting the plane of a front axle of a motor vehicle, a wedge comprising two members the bottom one having a pin for engaging the recess in the axle and a hub formed with a recess to receive the pin of the lower leaf of a front spring, the said members having intermeshing teeth formed on the same arc of a circle, whereby the upper member may be adjusted relative to the

lower member to offset the caster or twist of an axle.

2. A spring and axle adjusting device, comprising two members, one of which is formed with a lower flat surface and a projecting pin, a hub part integral with the lower member having an opening therein, the upper member having an opening to receive the hub part and the two members each having teeth formed on the arc of a circle which is common to both members and intermeshing teeth on the arc of the two members. 70 75

3. A spring and axle adjusting device, comprising two members, one of which is formed with a lower flat surface and a projecting pin, a hub part integral with the lower member having an opening therein, the upper member having an opening to receive the hub part and the two members each having teeth formed on the arc of a circle which is common to both members and intermeshing teeth on the arc of the two members, an end portion of one of the members being thicker than its opposite end portion, whereby when it is adjusted end for end a greater adjustment may be made. 80 85 90

4. A wedge device for the purpose described, comprising two members each having a flat surface and intermeshing teeth formed on an arc that is common to both members, one of the members having a boss part and the other an opening to receive the boss part to permit the members to be adjusted relative to each other. 95 100 105

5. A wedge device for the purpose described comprising two members each having a flat surface and intermeshing teeth formed on an arc that is common to both members, one of the members having a boss part and the other an opening to receive the boss part to permit the members to be adjusted relative to each other, the member with a boss part having a recess therein and the other member having a pin whereby the device may be installed between the front axle and the lower leaf of the front springs. 110

6. A two-part wedge for the purpose described, one of the parts having an end thicker than its opposite end and each part having intermeshing teeth formed on a common arc, co-operating means to permit the parts to be adjusted relative to each other in a longitudinal direction, as described. 115 120
